CLAIM

The ornamental design for a taco plate, as shown and described.

DESCRIPTION

FIG. 1 is a top, front perspective view of a taco plate showing our new design;

FIG. 2 is a top plan view thereof;

FIG. 3 is a left side elevational view thereof;

FIG. 4 is a front side elevational view thereof;

FIG. 5 is a rear side elevational view thereof;

FIG. 6 is a right side elevational view thereof, which is a mirror image of the left side elevational view; and, FIG. 7 is a bottom plan view thereof.
